ULTRA HIGH FREQUENCY FOR THERAPEUTIC PURPOSES

Ilia E. Mouromtseff, Montclair, N. J., assignor to Westinghouse Electric & Manufacturing Company, East Pittsburgh, Pa., a corporation of Pennsylvania

Application April 24, 1937, Serial No. 138,804

4 Claims. (Cl. 128—422)

My invention relates to high frequency devices and especially to apparatus and method for treating the human body with ultra high frequency.

An object of my invention is to provide a treatment of the human body in which there is no danger of sparking between the patient's body and the apparatus.

Another object of the invention is to provide a treatment which removes the necessity of the attendant receiving a certain amount of radiation together with the patient.

A still further object of my invention is to utilize standing waves.

A still further object of my invention is to utilize a radiating antenna and a reflector for treating the human body with high frequency.

Other objects and advantages of my invention will be apparent from the following description and drawing, in which:

Figure 1 is a perspective view of a patient being treated by means of a preferred form of my apparatus;

Fig. 2 is an end view of a modified form of apparatus of that of Fig. 1;

Fig. 3 is a perspective view of a still further modification of my invention; and

Fig. 4 is a perspective view of a type of apparatus for treating small parts of the body.

High frequency has been utilized in the treatment of the human body, and especially for producing an artificial fever therein. The method heretofore used has been to locate the patient or parts of his body between the plates of a condenser, which is part of an oscillating circuit. This type of treatment also includes the danger that there may be sparking between the patient's body and the condenser, and also that the attendant will receive a certain amount of the radiation together with the patient.

My invention, on the other hand, contemplates using high frequency in a form that will eliminate any sparking between the patient and the electric circuit. It eliminates the possibility of burning or blistering a patient and removes him from the immediate environment of the oscillating equipment, which, with some patients, causes undue excitement. My invention also permits of the positioning of the high voltage and bulky equipment in remote places. In its specific form, I contemplate utilizing a radiating antenna and directing the energy by means of back reflectors towards the patient.

In Fig. 1, I have illustrated the patient 10 reclining on a rest 11, which may be in the form of a table or couch, preferably containing no

metal. Above the rest 11 is a radiating antenna 12 extending parallel to the rest 11, and preferably having a length of the order of the patient's length. Suitable connections 13 and 14 extend to the high voltage oscillating circuit (not shown), which preferably produce standing waves on the radiating antenna 12. A reflector 15 is located above the radiating antenna 12 to direct the radiant energy towards the patient's body.

The distance between the antenna and the reflector is approximately $\frac{3}{8}$ to $\frac{1}{4}$ of a wave length. The reflector 15 is preferably in the form of a parabolic mirror. The height of the patient above the floor is also preferably of the order of $\frac{3}{8}$ to $\frac{1}{4}$ of a wave length. The high frequency oscillations are fed into the radiating antenna 12, and the radiations therefrom with the aid of the reflector 15 will be directed downward upon the patient in what might be called a radio bath or radio shower.

In Fig. 2, I have disclosed a similar arrangement of rest 11, patient 10, and radiating antenna 12. I have, however, enclosed the patient within a metal shield or screen 16 to prevent the escape of any radiation therefrom. I have also utilized a reflecting wire 17 that is located above the radiating antenna a distance of $\frac{3}{8}$ to $\frac{1}{4}$ of a wave length. This reflecting wire is similar in action to the reflecting mirror 15, and could be used in place of the mirror 15 in Fig. 1. The high frequency energy will be directed downward upon the patient.

In case it is desired to treat the patient while in the vertical position, I provide a radiating antenna comprising the two members 18 and 19 connected by conductors 20 and 21 to the high frequency apparatus. A large parabolic reflector 22 surrounds this antenna to direct the energy towards the patient 10, who stands at the focal line of a cylindrical parabolic reflector 23. The two parts 18 and 19 of the radiating antenna are, of course, preferably on a line with the patient's body.

In Fig. 4, I have illustrated apparatus for the treatment of small parts of the human body, such as the knee 24. This apparatus comprises a radiating antenna of two longitudinal parts 25 and 26 located within the reflector 27. This reflector is preferably in the form of a parabolic mirror, and will direct beams directly at the desired portion of the human body. A back reflector could also be used if desired.

It will be noted that in the above treatments, the patient cannot come into direct contact with the generating apparatus usually carrying the

high frequency charges and sometimes low frequency and direct current charges. The amount of energy dissipated in the human body can be easily regulated by changing the distance between the radiating antenna and the human body, or between the radiating antenna and the reflector, or in providing an adjustment of the height of the rest 11. The variation of the useful energy can also be effected by changing the antenna coupling to the generating circuit. The human body does not influence the adjustment of the oscillating circuit, as is the case with the condenser type previously referred to. The energy dissipated in the body can also be increased by having the patient hold in his hands pieces of metal tubing extending parallel to the antenna, and also by attaching metal surfaces to his feet. The disclosure is applicable to very short waves such as those of a high frequency of the order of 60 megacycles and higher.

While I have shown and described certain preferred modifications, it is apparent that many modifications may be made, including the form, arrangement and elements of my invention, without departing from the spirit thereof.

I claim as my invention:

1. Apparatus for treating a patient with high

frequency which comprises a non-metallic rest for the patient, a radiating antenna above said rest, a reflector above said radiating antenna, and a metal screen enclosing said rest, antenna and reflector.

2. Apparatus for treating a patient with high frequency which comprises a non-metallic rest for the patient, a radiating antenna above said rest parallel to said rest, a reflector above said radiating antenna, and a metal screen enclosing said rest, antenna and reflector.

3. Apparatus for treating a patient with high frequency which comprises a non-metallic rest for the patient, a radiating antenna the order 15 of the patient's length and located above said rest, a reflector above said radiating antenna, and a metal screen enclosing said rest, antenna and reflector.

4. Therapeutic apparatus comprising an antenna disposed to transmit radiations to a patient and a reflector spaced a distance of the order of $\frac{1}{4}$ to $\frac{3}{4}$ of the wave length of said radiation from said antenna and disposed to reflect the radiation emitted from said antenna to said patient.

ILIA E. MOUROMTSEFF.
